(57) **CLAIM**

(21) Appl. No.: **29/499,469**

The ornamental design for an elongated side handle for cookware, as shown and described.

(22) Filed: **Aug. 15, 2014**

DESCRIPTION

(51) **LOC (10) Cl.** **07-02**

FIG. 1 is a perspective view of a first embodiment of the elongated side handle for cookware showing my new design; FIG. 2 is a right side elevation view thereof; the left side elevation view being the mirror image thereof;

(52) **U.S. Cl.**

FIG. 3 is a top plan view thereof;

USPC **D7/395**

FIG. 4 is a bottom plan view thereof;

(58) **Field of Classification Search**

FIG. 5 is a front elevation view thereof;

USPC D7/354-361, 393-395, 401.2, 664;

FIG. 6 is a rear elevation view thereof;

D8/107, 300, 303, 307, 313, 321;

FIG. 7 is a perspective view of a second embodiment of the elongated side handle for cookware showing my new design; FIG. 8 is a right side elevation view of the second embodiment; the left side elevation view being the mirror image thereof;

D4/138, 129; 16/421, 430, 431, 110.1,

FIG. 9 is a top plan view of the second embodiment;

16/407; 220/573.1-573.5, 752, 753, 755,

FIG. 10 is a bottom plan view of the second embodiment;

220/756, 759, 767, 771, 912

FIG. 11 is a front elevation view of the second embodiment;

CPC .. A47J 45/071; A47J 45/072; B65D 25/2802;

FIG. 12 is a rear elevation view of the second embodiment.

B65D 25/2882; B65D 25/2888; B65D

The broken lines in FIGS. 1-12 are for illustrative purposes

25/2894; Y10S 220/912

only, depicting the environment of the new design, forming

no part thereof as claimed.

See application file for complete search history.
